UNITED STATES PATENT OFFICE.

CLARKE W. RIDER, OF DALLAS, TEXAS.

BOX AND CLOSURE LOCKING DEVICE.

1,183,770.

Specification of Letters Patent. Patented May 16, 1916.

Application filed March 19, 1915. Serial No. 15,566.

To all whom it may concern:

Be it known that I, CLARKE W. RIDER, a citizen of the United States, residing at Dallas, in the county of Dallas and State of Texas, have invented new and useful Improvements in Box and Closure Locking Devices, of which the following is a specification.

An object of the invention is to provide a simple device that can be quickly manufactured and which is preferably used on boxes, although it may be used on other receptacles for locking the cover or closure thereto.

The invention contemplates, among other features, the provision of a device which, used in connection with a box or receptacle, forms a lock box, in which, when the cover or closure is arranged upon the box, said cover or closure will be locked thereto and thus necessitate the mutilation of the box or cover before access can be had to the contents of the box.

In the further disclosure of the invention reference is to be had to the accompanying drawings, constituting a part of this specification, in which similar characters of reference denote corresponding parts in all the views, and in which:

Figure 1 is a fragmentary perspective view of a box showing my device applied thereto; Fig. 2 is a fragmentary perspective view of a closure showing my device applied thereto, parts being broken away to disclose the underlying structure; and Fig. 3 is a vertical longitudinal sectional view taken through the box and closure showing the interlocking arrangement.

Referring more particularly to the views, I disclose a box or receptacle 10 and a closure 11 therefor, said closure having sliding engagement with the box 10 and in this instance shown to slide longitudinally of said box, as in the nature of a box adapted to contain a deck of cards, with a sliding closure of a telescopic nature. The locking means in each instance consist of a single piece of material 12 of preferably strip metal which is bent in a substantially rectangular form to provide a side portion 13 and end portions 14. The piece of material is pressed through the edge of the box so that the portions 14 will pass transversely through the edge of the box and the side portion 13 will extend longitudinally of the box and lie against the inner face of the

edge, ends 15, 16 of the piece of material forming the outer side portions being bent upon the outer face of the edge of the box and then bent away from said outer face, 60 with the end 15 formed in a U-shape and the end 16 bent around to have its extremity lie between the portions 17 and 18 forming the U-shaped part of the end 15 so that the U-shaped part will form a projection 19 65 which is an extension of the part on the cover. The same construction described is duplicated on the closure 11 except that the projection 20 similar to the projection 19 which is an extension of the part 20 on the 70 box and as shown, a pair of the locking devices mentioned is provided on each edge of the box and each edge of the closure.

Now when the box has been filled with the desired contents the closure is slid on to the 75 box, with the closure sliding downwardly upon the box. Now as the two opposed projections pass each other, it will be seen that the projection on the closure will spring past and toward said closure and the projection on the box will spring past and toward the closure so that after the box and closure have been locked and it is endeavored to separate the same the projections will 80 interlock with each other and prevent removal 85 of the closure except by mutilation of the closure to an extent which will permit of relatively interlocking the projections from each other.

From the foregoing description it will be 90 seen that the locking devices on the box and closure are the same in each instance, but are merely reversed, with the locking projection on the box extending in an opposite direction to the locking projection on 95 the closure, each being formed of the same kind of spring-like strip metal fastened to its particular member in substantially the same manner, with one of the ends of each piece of spring-like strip metal bent into the 100 U-shaped portion of the other end and crimped therein by having said U-shaped portion of the other end overlying the end extending between the sides of the U-shaped portion.

Having thus described my invention, I claim:

1. A means for locking a closure to a box, comprising a member applied to the closure and a member applied to the box, 110 each of said members consisting of a single piece of spring-like strip metal having por-

tions extending through a wall of said closure or box, with the ends of said piece of metal lying outside of the wall, one end bent to form a U-shaped portion and the 5 other end bent around to lie between the sides of the U-shaped portion and be wedged therein to form a projection, with the projection of one of the members extending in one direction and the projection 10 of the other member extending in the other direction, whereby when said closure and box are associated with each other the said projections will interlock and prevent relative movement of the closure and box.

15 2. A means for locking a closure to a box comprising a member applied to the closure

and a member applied to the box, each of said members consisting of a single piece of spring-like strip metal having portions extending through a wall of said closure and 20 box with the ends of said piece of metal lying outside of the wall, one end being engaged with the other end of the metal to prevent relative movement of the closure and box.

25

In testimony whereof I affix my signature in presence of two witnesses.

CLARKE W. RIDER.
